UNITED STATES PATENT OFFICE.

GEORGE L. BENSON, OF ST. MICHAEL'S, MARYLAND.

REFRIGERATOR-CAR.

SPECIFICATION forming part of Letters Patent No. 642,418, dated January 30, 1900.

Application filed October 30, 1899. Serial No. 735,249. (No model.)

To all whom it may concern:

Be it known that I, GEORGE L. BENSON, a citizen of the United States, residing at St. Michael's, in the county of Talbot and State 5 of Maryland, have invented a new and useful Refrigerator-Car, of which the following is a specification.

The invention relates to improvements in refrigerator-cars.

10 One object of the present invention is to improve the construction of refrigerator-cars and to provide a simple and comparatively inexpensive one which will permit a free circulation of cold air through its contents and 15 which will be especially adapted for carrying fruit.

A further object of the invention is to provide a refrigerator-car of this character adapted to divide the weight of the load, and thereby 20 prevent the entire weight of the same from resting upon the bottom boxes or layers, whereby the liability of bruising, ripening, or otherwise injuring fruit is reduced to a minimum.

25 Another object of the invention is to enable the supporting devices for sustaining the upper half of the contents of the car to be compactly folded against the sides of the latter when the car is not employed for carrying 30 fruit.

The invention consists in the construction and novel combination and arrangement of parts hereinafter fully described, illustrated in the accompanying drawings, and pointed 35 out in the claims hereto appended.

In the drawings, Figure 1 is a longitudinal sectional view of a refrigerator-car constructed in accordance with this invention, the supports being in position for use in one 40 half of the car and being folded at the other half of the car. Fig. 2 is a transverse sectional view on line 2-2 of Fig. 1, the supports being in position for use. Fig. 3 is a perspective view showing the inner face of one side 45 of the car and illustrating the manner of folding the supports. Fig. 4 is a detail sectional view, the parts being arranged as shown in Fig. 3. Fig. 5 is a detail perspective view of the block which supports the free end of the 50 folding transverse bar when the latter is in position for use.

Like numerals of reference designate cor-

responding parts in all the figures of the drawings.

1 and 2 designate vertical bars or cleats secured, respectively, to the inner faces of the sides and ends of a refrigerator-car 3 and having horizontal slats 4 and 5 secured to them and arranged at intervals to form side and end walls of the refrigerating-compartment of the car. The side and end walls are spaced from the sides and ends of the car by the vertical bars and cleats 1 and 2, which are provided with suitable recesses 6 and 7 to permit a circulation of air through the spaces 65 formed by them. The slats are spaced apart to provide openings for the passage of air and to permit the latter to pass freely from the interior of the car to the side and end passages or spaces formed by the side and end 70 walls. The car is provided at its bottom with a supporting-platform 8, preferably composed of two sections and consisting of longitudinal slats secured to transverse bars 9, which offset the slats from the bottom of the car to 75 provide spaces to permit air to pass beneath the contents of a car from one side to the other of the latter.

Supported upon the walls of the refrigerating-compartment is a shallow pan 10, forming an ice-receptacle and constituting the top of the refrigerating-compartment of the car. The walls of the ice-receptacle may be of any height to provide a pan of any depth, and they have horizontal supporting-flanges 11 85 and 12 extending outward from the sides and ends of the receptacle and resting upon the side and end walls formed by the slats 4 and 5. The side flanges 11 terminate short of the side walls of the car; but the end flanges 12 90 extend to the end walls of the car and close the vertical end spaces or passages at the top, whereby the cold air is caused to descend at the sides of the car. The ice is supported upon platforms or trays 13, composed of longitudinal slats and transverse bars, which are recessed at their ends 14 to provide passages for the escape of water to permit the same to flow to drain-tubes 15, which are located at diagonally-opposite corners of the car. The 100 drain-tubes 15, which are suitably secured to the inner slatted walls of the car, are preferably provided between their ends with goose-neck bends 16 to provide water seals, and

thereby prevent cold air from passing out through the drain pipes or tubes.

The car is provided at its sides and ends above the ice-receptacle with vertical blocks 5 or pieces 17 and 18, to which are secured side and end slats 19 and 20, arranged in the same plane as the inner side and end walls and adapted to prevent any ice of the receptacle from getting into the spaces between the inner walls and the car-body.

The ice-receptacle is divided into two separate portions or compartments by a transverse partition 21, depending from the top of the car-body and extending entirely across 15 the same. Ice is supplied to the receptacle from the top of the car, which is provided with doors 22, located at opposite sides of the transverse partition, and it will be readily apparent that either or both of the compartments of the ice-receptacle may be used.

In order to relieve the bottom platform of one-half of the weight of the fruit to avoid bruising the same and the heating resulting from close contact, horizontal shelves or partitions 24 are employed and are adapted to fold against the sides of the car or, rather, the inner walls thereof, as illustrated in Fig. 3 of the accompanying drawings. The shelves or partitions, which extend from the door-opening to the inner end walls of the car, are connected to the inner side walls by hinges 25, which permit the shelves or partitions to swing upward against the said inner side walls, in which position they are secured by 35 suitable fastening devices when it is desired to use the car for meats and the like. When the partitions or shelves are in a horizontal position, they are supported by and rest upon transverse bars 26 and 27, which enable them 40 to sustain the weight of the upper half of the contents of the car. The hinged shelves or partitions are preferably constructed of longitudinal slats connected by suitable cross-bars; but they and the inner walls of the car 45 may be constructed in any other suitable manner, if desired.

The outer transverse bar 26 is secured to the inner end wall by suitable fastening devices and is stationary. The inner transverse supporting-bar 7 is connected at one end with the adjacent slatted side wall by a hinge 28, arranged at one of its side faces and adapted to permit it to swing against such slatted side wall to fold it in the position illustrated in Fig. 3 of the accompanying drawings. Its free end is supported when it is in position for use by a vertical block or piece 29, recessed at its upper end to provide a pair of lugs 30, which engage the side faces 50 of the bar 27, whereby the latter is securely held on the support. The free end of the bar 27 is supported by a block 32 when the parts are folded, as shown in Fig. 3, and the said block 32 is provided with a vertical lug or 55 projection, which retains the bar 27 in its folded position. When the bar 27 is folded, it is arranged beneath the adjacent shelf or

partition, which is then in a vertical position. The shelves or partitions when in position for use are adapted to support a portion of the 70 contents of the car, and they prevent the lower boxes or layers of fruit from being subjected to the weight of the entire contents of the car. This will reduce the liability to bruise fruit, berries, and the like to a minimum and will prevent the heating and consequent ripening resulting from fruit being packed too closely.

It will be seen that the ice in the pan or receptacle at the top of the car reduces the 80 temperature of the air at that point, which being heavier than the air at the bottom of the car descends at opposite sides of the latter and produces a thorough circulation. The slatted inner walls, the bottom platform, and the slatted supports permit the cold air to have thorough access to the entire contents of the car, and the transverse partition at the top of the car will admit of the use of either or both of the compartments of the ice-receptacle.

Changes in the form, proportion, size, and the minor details of construction within the scope of the appended claims may be resorted to without departing from the spirit or 95 sacrificing any of the advantages of this invention.

What is claimed is—

1. In a refrigerator-car, the combination with the car-body, of the inner side and end walls, spaced from the car-body and having openings, and the ice-receptacle supported by the said inner walls at the top of the car and provided with horizontal side and end flanges resting upon the said inner walls, the end 105 flanges being extended across the spaces between the walls to close the same, and the side flanges terminating short of the sides of the car-body, whereby the cold air is forced to descend at the sides of the car, substantially 110 as and for the purpose described.

2. In a refrigerator-car, the combination with the car-body, of the inner side and end walls spaced from the car-body and having openings, the ice-receptacle located at the top 115 of the car and supported by the inner walls and provided with horizontal flanges resting upon the same, the side flanges terminating short of the car-body and the end flanges extending to the same, blocks mounted on the 120 body of the car at the sides and ends thereof, above the ice-receptacle, and the side and end slats secured to the said blocks, substantially as described.

3. In a refrigerator-car, the combination 125 with the car-body, of the inner side and end walls spaced from the car-body and having openings, the ice-receptacle arranged at the top of the car and supported by the said inner walls and provided with side and end 130 flanges resting upon the same, the side flanges terminating short of, and the end flanges being extended to the car-body, blocks mounted on the car-body at the sides and ends of the

same and located above the ice-receptacle, the side and end slats secured to the blocks, and the transverse partition extending across the car-body and depending into the ice-receptacle and dividing the same into separate compartments, substantially as described.

4. In a refrigerator-car, the combination of the horizontal shelves or partitions arranged in pairs and hinged at opposite sides of the car and adapted to swing upward to fold, a horizontal supporting-bar located beneath the shelves or partitions and hinged at one end and arranged to swing across the car and adapted to be arranged at one side thereof when the parts are folded, and blocks mounted at opposite sides of the car and provided with lugs and adapted to receive and support the free end of the said transverse bar in its folded and operative positions, substantially as described.

5. In a refrigerator-car, the combination with a car-body, of inner side and end walls spaced therefrom, a fixed horizontal bar mounted on the end wall, a folding horizontal bar hinged to one of the side walls and arranged to swing across the car, blocks mounted on the side walls and arranged to receive the free end of the folding bar, and the folding shelves or partitions hinged to the side walls above the said bars and arranged to swing downward upon the same, substantially as and for the purpose described. 25 30

In testimony that I claim the foregoing as my own I have hereto affixed my signature in the presence of two witnesses.

GEO. L. BENSON.
